UNITED STATES PATENT OFFICE.

ALEXANDER JOHN ARBUCKLE, OF JOHANNESBURG, TRANSVAAL, ASSIGNOR OF ONE-HALF TO THE ANGLO FRENCH EXPLORATION COMPANY, LIMITED, OF LONDON, ENGLAND.

ORE-TREATING APPARATUS.

1,036,535.

Specification of Letters Patent. Patented Aug. 27, 1912.

Application filed June 21, 1909. Serial No. 503,508.

To all whom it may concern:

Be it known that I, ALEXANDER JOHN ARBUCKLE, a subject of the King of Great Britain, and resident of Johannesburg, Transvaal, have invented certain new and useful 5 Improvements in Ore-Treating Apparatus, of which the following is a specification.

This invention relates to a means or apparatus primarily designed for separating 10 crushed ore products from water, cyanid or other solutions, wash-water or other liquid.

As examples of the uses to which my invention may be advantageously put in metallurgical operations, I may instance the separation 15 of the particles of ore from the liquid of "battery pulp"—the mixture of crushed ore products and liquid as it comes from the crushing or reduction plant—and the separation of any of the aforementioned 20 liquids from "sands"—the coarse particles of crushed ore products—or "slimes"—the fine particles of such products.

The invention is also equally applicable for continuously separating the liquid and 25 solid components of other fluid masses.

The apparatus may be adapted for dealing 30 with fluid masses containing either a high or low percentage of comminuted solid matter. By its use it is possible to obtain a uniformly and exceptionally dry product, so eminently desirable in wet metallurgical processes.

In the construction of my improved apparatus I employ a vessel of the requisite 35 capacity to serve as a receiver for the pulp, fluid mass or mixture of solids and liquid to be separated. In this vessel the separation of the solids and liquid is effected. The solid component of the pulp or mass, being 40 the heavier, gravitates or falls to the bottom of the vessel, while the liquid component either overflows, or is withdrawn through suitable filters, or both. This receiving vessel is constructed for the whole or any suitable portion of its height with downwardly and inwardly inclined or converging sides.

To the bottom of the receiving and settling vessel is affixed a piece or casting which is constructed interiorly to provide one or a 50 plurality of lateral chambers or compartments. These chambers or compartments may be formed either singly or in groups and in any suitable position or positions around the piece of casting. For each lateral

chamber or compartment I provide a conveyor, consisting of a shaft around which are helically disposed blades or plates in the form of an intermittent screw-thread. The construction of this screw conveyor (or screw conveyers) is an important feature of 55 my invention. A portion of one end of the screw works in the lateral chamber. The remainder of the screw is inclosed by a suitable casing which at one end is connected with the piece or casting and at the other 60 end suitably carried by the structure supporting the receiving vessel, or otherwise.

When a plurality of conveyers is employed arranged in one or more groups, then the conveyer casing for each group is divided into a number of separate compartments, corresponding to the number of conveyers provided in the group. The screw conveyer or conveyers may be arranged either with their axes horizontal or at any 75 desired inclination, in order to lift the separated solids to any desired point, say into another vessel. The shaft or shafts of the conveyer or conveyers run in suitable bearings at each end. The conveyer or conveyers may be driven from either or both 80 ends of its or their shaft as preferred or found most convenient in practice.

The solids, which are collected in the bottom of the receiving vessel and pass into the 85 lateral compartment or compartments, are removed therefrom and carried along or up the conveyer casing by the action of the screw conveyer or conveyers. Arrangement may be made for putting any one or more 90 of the conveyers out of operation, as found necessary or desirable according to the quantity of solid matter contained in the mixture being treated.

When intended more particularly for 95 dealing with a fluid mass containing a low percentage of comminuted solid matter, I preferably provide in the receiving vessel a filtering device or devices for removing or assisting in the removal of the liquid component of the mass from said vessel. Any desired number of such filters or filtering devices may be provided and be arranged in tiers or otherwise inside the vessel in suitable positions below the level of the overflow and above the normal level of the settled solids. These filters may be so arranged that any particular filter or set or 100 105

sets of filters can be brought into operation as required according to the percentage of liquid contained in the pulp or mixture being separated.

5 The filters may conveniently comprise suitably shaped skeleton frames covered preferably top and bottom with wire screening or perforated plates and canvas or other suitable filtering material or materials. 10 The frames are connected with suction and preferably also with back pressure creating means, the former for drawing the liquid component through the interstices of the filtering media, and the latter, when desired, 15 for cleansing the exterior surfaces of the filtering media of any adhering solid matter. The filters are co-operatively associated with means for scraping or removing the solid matter, or a portion thereof from the exterior surfaces of the filtering material. 20 These means may comprise a vertical shaft to which is attached a plurality of radial arms arranged to work horizontally between the several sets or tiers of filters and above the uppermost and below the lowermost set 25 or tier. Each of the arms has affixed to it by means of brackets and tension screws one or more wires or thin metal strips or bands for cutting or severing the solids deposited on the exterior surfaces of the filtering material. 30 The arms which move above the upper surfaces of the top set or tier of filters and the arms which move beneath the lower surfaces of the bottom set or tier of filters are provided with one wire or thin metal strip, 35 while the arms which work between the several sets or tiers of filters are provided with two of such wires or metal strips, one for the lower surfaces of the upper set or tier of filters, and the other for the upper surfaces of 40 the lower set or tier of filters.

The wires or metal strips or bands are so disposed that they sever the layer of solid matter as close as possible to the surfaces of 45 the filtering material. The arms which carry the wires or metal strips or bands serve to scrape or remove the layer of solid matter severed by the wires or bands, and to deliver it over a vertical passage formed by and between the several sets or tiers of filters. If desired, the means for severing the layer of solids deposited on the filters may be dispensed with and the apparatus be so arranged that the back pressure flow 50 through the filters takes place while the arm or arms are passing over said filter or filters.

The several filters comprising each set or tier are supported inside the vessel by suitable carriers or frames fixed to the vessel at 55 the outer ends and connected together at their inner ends. These frames are so disposed that an unobstructed passage is formed between the several filters of each set or tier and between all the tiers so that the 60 solids scraped off the filters can fall freely

to the bottom of the vessel. The filters of each tier from the top to the bottom of the vessel are made somewhat smaller or narrower than those of the tier above, and the filter carriers from the top to the bottom of 70 the vessel are made correspondingly wider. This construction allows the filters of each set or tier to pass freely through the carriers of the sets or tiers above, and thereby facilitates the removal of the filters from the vessel. The vertical shaft which is utilized to 75 actuate the scrapers has preferably affixed to it in its lower portion a plurality of radial arms for feeding or delivering the settled solids into the lateral chamber or chambers. 80

The pulp or mixture is preferably introduced into the vessel by means of an interiorly slotted annular feed pipe, which is positioned at a suitable point below the level of the lowermost set or tier of filters, and above the normal level of the settled solids. An annular overflow or rim launder is preferably provided around the top of the receiving and settling vessel to receive the overflowing clear liquid. A water supply is 90 preferably provided for the bottom bearing of the scraper shaft to keep it clear of solids or gritty matter. If desired, means may also be provided for introducing a supply of water into the lower end of each of the lateral compartments. When a number of the conveyors are arranged in a group one of the group may be driven directly and the others driven from it by means of suitable toothed wheels. Stuffing boxes and glands 95 are provided around the conveyer shaft or shafts to prevent the egress of the liquid. The conveyer shaft or shafts and also the scraper shaft may be driven by worms and worm wheels or in any other suitable manner. 100

In the accompanying drawings, which form part of this specification, I illustrate a practical embodiment of my invention.

In the drawings Figure 1 is an elevation 110 of the apparatus with a portion of the screw conveyer casing broken away to show a portion of one of the screws. Fig. 2 is a plan of the piece or casting which is fixed to the bottom of the vessel and is constructed to provide the lateral compartments for the conveyer screws. Fig. 3 is a view of that portion of the piece or casting forming the lateral compartments, as seen from the underside. Fig. 4 is a plan of the receiving vessel illustrating the frames or carriers for the filters and one of each of the three sets or tiers of filters in position. Fig. 5 is a sectional elevation of the upper portion of the vessel illustrating the three sets 125 of filters, their carriers and the scrapers for removing the solid matter. Fig. 6 is a longitudinal section of one of the top set or tier of filters. Fig. 7 is a transverse section of Fig. 6 showing the filtering material in posi- 130

tion on the top and bottom of the skeleton frame. Fig. 8 is a view similar to Fig. 6 of one of the intermediate set or tier of filters. Fig. 9 is a transverse section of Fig. 8. Fig. 10 is a view similar to Figs. 6 and 8 of one of the bottom set or tier of filters. Fig. 11 is a transverse section of Fig. 10. Fig. 12 is a plan of the apparatus with the filters and filter carriers removed showing the scrapers and their actuating means. Fig. 13 is an elevation of the outer end of one of the scraper arms showing the means for fixing the wires or bands which cut the solid matter deposited on the filters. Fig. 14 is an elevation of a portion of the other end of the arm also illustrating the means for fixing the wires or bands. Fig. 15 is a transverse section of Fig. 13 on the line $x-x$. Fig. 16 is a plan of Fig. 13. Fig. 17 is an end elevation of the conveyer screw. Fig. 18 is an elevation of one of the helically disposed plates of the conveyer screw. Fig. 19 is a section of Fig. 18. Fig. 20 is a horizontal section of the receiving vessel illustrating the construction and arrangement of the pipe for introducing the pulp or mass into the vessel. Fig. 21 is an elevation of one of the filters, detached and drawn to an enlarged scale, illustrating the means for fixing thereto the filtering fabric. Fig. 22 is a plan of one of the clamping bands 45 for fixing the filtering fabric 44 around the skeleton frame 41 of the filter.

1 represents the receiving vessel with con verging bottom. It may, as shown in Figs. 1 and 12, comprise a hollow cylindrical upper portion, extending to any desired and suitable height, and a hollow inverted and truncated conical lower portion; or, as shown in Figs. 4 and 5, it may be in the form of a hollow inverted conical frustum, and the hollow cylindrical upper portion be dispensed with.

2 represents an annular overflow or rim launder surrounding the upper edge of the vessel 1. This launder 2 serves for receiving the clear liquid overflowing from vessel 1. When no filters are provided in the receiving vessel 1, then launder 2 serves for receiving all the clear liquid. When the filters are employed I prefer to provide the settling vessel 1 with the launder 2 to receive the liquid in case it should overflow, or to receive a portion of the liquid when the filters are used for assisting in the removal of the liquid from the vessel 1. The vessel 1 is carried by a suitable frame work comprising the several members 3.

4—see Figs. 1, 2 and 3—is the hollow piece or casting which is positioned at and fitted to the bottom of the vessel 1. It is constructed at the top, as indicated at 5, to receive the lower end of the conical portion of the vessel 1 and make a fluid tight joint therewith. It closes the bottom of the ves-

sel 1, and is shown constructed on the one side—see Fig. 2—to provide three lateral chambers or compartments 6, all communicating with the interior of the casting 4 and vessel 1.

7—see Fig. 2—are webs formed on the inside of the casting 4 which divide the three chambers 6. The casting 4 is supported in position beneath the vessel 1 on the one side by means of the legs or supports 8,—which at their upper ends are attached to the casting and at their lower ends are secured to the base plate 9—and on the other side by means of the standard or support 10 fixed to the base plate 9 and to the casting 4. The lower end of that portion of the casting 4 which provides the three lateral compartments 6 is closed by means of a plate 11, which is bolted or otherwise secured to a flange 12 formed upon the casting 4. Plate 11 is constructed to provide three stuffing boxes 13 one for each of the lateral compartments 6—see Fig. 3. 14 represent the shafts of the three screw conveyers, one arranged in each of the three compartments 6. The shafts 14 at their lower ends project through the stuffing boxes 13—which latter have glands 15 for preventing the egress of liquid from the casting. The shafts of the two outside conveyers run in footstep or other suitable bearings 16 carried by supports 17 fixed between the legs 8 and the standard or support 10. The shaft of the center conveyer, which is somewhat longer than the other two, runs in a footstep or similar bearing 18 fixed to the base plate 9. In the arrangement shown the three conveyer shafts 14 are driven from the bottom, but it is to be understood that they may, if preferred, be driven from the top, or from both bottom and top.

The driving means for the shafts 14 are shown comprising a shaft 19 on which is provided a worm 20 gearing a worm wheel 21 fixed on the intermediate shaft 14. The motion is transmitted from the intermediate shaft 14 to the two outside shafts 14 by a toothed wheel 22 fixed to said intermediate shaft gearing toothed wheels 23 fixed on the outside shafts. Although I show the casting 4 constructed for one group of three conveyers it is apparent that it might be constructed for more or less, and that they might be arranged either singly or in groups of two or more in any suitable positions 120 around the casting.

24 is the casing which incloses those portions of the three screw conveyers which extend beyond the casting 4. This casing, which when in position forms a continuation of the three lateral compartments 6, is rectangular in cross section and is provided with two partitions corresponding to the webs 7 in the casting 4. It may be constructed of wood or other suitable material. 130

The casting 4 is recessed or constructed as indicated at 25 to receive and support the lower end of the casing 24. The other and upper end of the casing 24 is shown carried by posts 26 and timbers 27. A beam 28 fixed to the timbers 27 serves for carrying the three bearings 29 for the upper ends of the shafts—see Figs. 1 and 12.

30 is a chute, which may be conveniently supported by the timbers 27, for receiving the solids carried up the casing 24 by the action of the three screw conveyers and discharged thereby through the open upper end of said casing. This chute may be arranged to deliver the solids into another vessel or into vehicles or other means for conveying them to any desired place. The casing 24 may be extended in an upward direction in order to raise the point of discharge of the solids if desired. It is shown arranged at the same inclination as the sides of the converging portion of the vessel 1 but it may be arranged horizontally or at any other suitable inclination.

25 The manner of constructing the screw conveyers will be readily understood on reference to Figs. 1 and 17 to 19 of the drawings. The shaft 14 of each conveyer is formed with flats, and the plates 31, which when threaded on the shaft form the intermittent screw thread or threads, are, as shown in Figs. 17 to 19, formed with a hole 32 at the center corresponding to the cross section of the shaft. The flat or flats in the hole 32 are so positioned in relation to the projection or projections 33, which form the intermittent helix or helices, as to maintain the plates 31 in correct position in relation to each other when threaded on the shaft. The plates 31, may, as shown, be constructed with the two oppositely disposed projections 33 to form a double-threaded screw, or they may be formed with one such projection so as to form a single-threaded screw, or with more than two of such projections to provide any desired number of threads.

34 in Figs. 18 and 19 represent projections formed on the plates for maintaining them the proper distance apart when upon the shaft. Instead of or in addition to the projections 34 separate distance pieces may be placed upon the shaft between the plates 31. The plates 31 may, as shown, be made flat so that the projections 33 each lie in a plane at right angles to the axis of their shaft; they may if preferred be suitably inclined to said axis.

35 represents a pipe which can be utilized, if found necessary or desirable, for conducting water or other suitable liquid into the bottom of the casting 4; one of such pipes 35 can be provided located at the center, or one for each compartment 6 if required.

65 In the arrangement illustrated in Figs. 1,

4 and 5, I show three sets or tiers of removable filters arranged in the vessel 1 but it is to be understood that a greater or less number of tiers may be provided and each tier consists of one or any desired number of filters. The filters will usually be provided when the mixture to be treated contains only a small percentage of comminuted solid matter. Each set or tier is shown comprising eight filters.

36 represents the top filters—one of which is shown in detail in Figs. 6 and 7—, 37 the intermediate filters—one of which is shown in detail in Figs. 8 and 9—and 38 the bottom filters—one of which is shown in detail in Figs. 10 and 11. The several filters of each set or tier from the top to the bottom are made somewhat narrower than the filters of the set or tier or sets or tiers above, so as to allow of their being readily removed from the vessel when necessary.

The carriers for the several sets or tiers of filters are clearly shown in Figs. 4 and 5. They comprise a horizontally arranged substantially rectangular frame 39, bolted, riveted or otherwise suitably fixed at the outer end to the inside of the vessel 1, and formed at the inner end with lugs or projections 40 which serve for bolting or otherwise suitably connecting the inner ends of all the frames in the form of a ring. The carriers for the intermediate and bottom tiers of filters are constructed and arranged in like manner. As shown in Fig. 4 the carriers for the intermediate tier of filters are somewhat wider than those for the top tier, and those for the bottom tier slightly wider than those for the intermediate tier, to correspond to the decrease in the width of the filters from the top to the bottom of the vessel.

The filters of the several tiers, as shown more particularly in Figs. 6 to 11, consist of a skeleton frame 41, which is ribbed transversely, top and bottom, as indicated at 42. These ribs 42 serve for carrying the wire screening or perforated plates 43 which are arranged in recesses formed in the top and bottom of the frame 41. Over the screening or plates 43 is preferably stretched canvas or other suitable textile fabric 44. The fabric 44 is secured upon the top and bottom of the frame 41 by means of clamping bands or wires 45 see Figs. 21 and 22 located in recesses or grooves 46 formed around the outside of the frame 41. The frames 41 are constructed with flanges, ledges or projections 47, which, when the filters are in position in the vessel, rest upon the rectangular frames 39 as shown in Figs. 4, 5, 7 and 11.

48 is a three-way piece screwed into or otherwise suitably fixed to the frame 41 and communicating with the interior thereof between the coverings of filtering material.

One branch 49 of the three-way piece 48 is coupled up to any suitable suction or vacuum creating apparatus for drawing the liquid component of the mass through the interstices of the filtering material. The other branch 50 of the three-way piece 48 is connected with any suitable back pressure creating means for producing, if and when desired, a back pressure, or a flow in the opposite direction to the suctional and filtering flow. Any suitable means may be employed for bringing the suction and back pressure apparatus into operation at any desired periods in the operation of the apparatus, say for closing the filters to suction and opening them to back pressure when the scrapers (hereinafter described) are passing over the surfaces of the filtering material. The operation of controlling the suction and back pressure apparatus may be effected by hand, in which case the suction can be maintained until such time as it is necessary to cleanse the filtering material by admitting the back pressure flow. The pipes or connections from the several filters may be provided with valves or other means for shutting off any particular filter or set of filters as may be required in the operation of the machine.

The means for removing the adhering solid matter which is deposited upon the surfaces of the filtering material comprise the vertical shaft 51. Shaft 51 at its lower end runs in a bearing 52 provided on the inside of the casting 4 and at or in proximity to its upper end in a bearing 53 carried by angle iron or other suitable members arranged across the top of the vessel. The rotary motion is imparted to shaft 51 by means of worm wheel 55 fixed to the upper end of the shaft gearing a worm 56 upon a driving shaft 57. Motion may be imparted to the shaft 57 by any convenient means to drive the shaft 51 at a suitable rate of speed, which will to some extent depend upon the quantity of solids contained in the mixture being treated. 58 represent horizontally arranged scraper arms which are fixed radially to the shaft 51 by means of hub members 59. As shown more particularly in Fig. 5, four sets of the radial arms are provided upon the shaft 51 and each set comprises four arms. The upper set of arms 58 works above the upper filtering surfaces of the top tier of filters, the two intermediate sets between the top and intermediate and intermediate and bottom tiers of filters, and the lower set beneath the bottom tier of filters.

Each of the scraper arms has fixed to it a wire or wires or thin metal band or bands 60 for cutting the solids as close as possible to the surface of the filtering material. In the case of the top and bottom sets of arms 58 one wire or band only is necessary, as these arms serve only for removing the solids

from the upper surfaces of the top filters and the lower surfaces of the bottom filters respectively. In the case of the two intermediate sets of arms 58 two wires or bands are requisite as these arms serve for removing the solids from the bottom of one tier of filters and also from the top of tier below.

For securing the wires or bands 60 to the scraper arms, brackets 61—see Figs. 13 to 16—are riveted or otherwise suitably secured at or in proximity to the inner and outer ends of the arms. Tension screws 62, which are formed with a square portion which passes through correspondingly shaped holes in the brackets 61, have attached to one end—see Figs. 13, 14 and 16—the end of the wire or band 60.

63 are nuts on the screws 62 for securing the latter in position after the wire or band has been made taut. By forming portions of the screws square and constructing the holes in the brackets 61 of the same shape it operates to maintain the bands horizontal and insures their taking a clean cut through the solids. The bands or wires 60 are attached to the arms in a manner that will admit of their passing as close as possible to the surfaces of the filtering material. It will be evident that after the solids have been severed by the bands the arms scrape the same off the surfaces of the filters and deliver them over the passages 64 formed between the filters by the carrier frames 39, down which they fall to the bottom of the vessel 1. For the purpose of feeding or delivering the settled solids to the lateral chambers or compartments 6, a number of radial blades or arms 65 are preferably secured in any suitable manner to the lower portion of the vertical shaft 51. These arms 65 may be inclined or twisted longitudinally so as to operate like a screw to force the solids in a downward direction.

66 represents a pipe for conducting water or other liquid to the bearing 52 provided in the casting 4 for the lower end of the shaft 51, in order to prevent the entrance of gritty matter and so obviate excessive wear.

67 is the annular interiorly slotted feed pipe—see Figs. 1 and 20.

68 in Fig. 20 indicates the pipe conveying the pulp or mixture to the feed pipe 67 from which latter it passes into vessel 1 through the slot 69—see Fig. 1. The feed pipe 67 is supported by means of a suitable bracket 70 fixed inside the vessel 1. The pipe 67 is located in a suitable position beneath the lowermost set or tier of filters and above the normal level of the settled solids.

The operation of the apparatus is perfectly obvious from the foregoing detailed description and need not be further described.

The construction of the screw conveyer

hereinbefore described constitutes the subject matter of an application filed May 15, 1911 Serial No. 627330 which is a division of the present application.

5. What I claim as my invention and desire to protect by Letters Patent is:—

1. In apparatus for the purpose described, in combination, a settling vessel having a converging bottom, a piece or casting arranged at the bottom of the settling vessel, said piece or casting being constructed with a plurality of lateral compartments communicating with the vessel, a plurality of conveyers for withdrawing the settled solids 10 from the vessel working in said lateral compartments, a casing for those portions of the conveyers working without said lateral compartments, said latter casing having separate compartments for each conveyer, 15 means for feeding said solids from the vessel into said lateral compartments, and means for driving the conveyers.

2. In apparatus for the purpose described, in combination, a settling vessel, a screw 25 conveyer for withdrawing the settled solids from said vessel, means for feeding the settled solids to said conveyer, said means comprising a vertical shaft and radial arms or blades, and means for conducting water to 30 the bearing for the vertical shaft to prevent the entrance thereinto of gritty matter.

3. In apparatus for the purpose described, in combination, a settling vessel, a piece or casting arranged at the bottom of the settling vessel, said piece or casting being constructed with a plurality of lateral compartments communicating with the vessel, a plurality of conveyers working in said lateral compartments for withdrawing the settled 35 solids from the vessel, a casing surrounding those portions of the conveyers extending beyond the lateral compartments, said casing having separate compartments for each conveyer, means for supporting the conveyer shafts, means for driving one of said 40 shafts, and means for driving the other conveyer shafts from the directly driven shaft.

4. In apparatus for the purpose described, in combination, a settling vessel having a 50 converging bottom, a piece or casting fixed to the bottom of said vessel said piece or casting having a lateral compartment, a screw conveyer for removing the settled solids arranged in said lateral compartment, 55 a casing for surrounding that portion of the conveyer without the lateral compartment, means located in the vessel for feeding the settled solids into the lateral compartment, said latter means comprising a vertical shaft and spirally disposed arms or blades upon said shaft.

5. In apparatus for the purpose described, in combination, a settling vessel, a conveyer for withdrawing the settled solids from said 60 vessel, means for feeding the settled solids

from the vessel to the conveyer, and means for introducing the mixture of solids and liquid into the vessel above the normal level of said settled solids.

6. In apparatus for the purpose described, 70 in combination, a settling vessel, a conveyer for withdrawing the settled solids from said vessel, means for feeding the settled solids from the vessel to the conveyer, and means for introducing the mixture of solids and liquid into the vessel above the normal level 75 of said settled solids, said latter means comprising an annular interiorly slotted feed pipe.

7. In apparatus for the purpose described 80 in combination, a settling vessel, a conveyer for withdrawing the settled solids therefrom, a casing inclosing said conveyer, said casing communicating with the settling vessel, means for feeding the settled solids from 85 the vessel to said casing, said means comprising a vertical shaft and radial blades or arms fixed to said vertical shaft, and filtering means in the vessel for removing or assisting in removing the liquid from the 90 vessel.

8. In apparatus for the purpose described in combination, a settling vessel, a conveyer for withdrawing the settled solids therefrom, a casing inclosing said conveyer, said 95 casing communicating with the settling vessel, means for feeding the settled solids from the vessel to said casing, said means comprising a vertical shaft and radial blades or arms fixed to said vertical shaft, and a plurality of filters arranged in tiers in the vessel, said tiers of filters being so constructed and supported as to provide free passages 100 between them from the top to the bottom of the vessel.

9. In apparatus for the purpose described in combination, a settling vessel, a conveyer for withdrawing the settled solids therefrom, a casing inclosing said conveyer, said casing communicating with the settling vessel, means for feeding the settled solids from the vessel to said casing, said means comprising a vertical shaft and radial blades or arms fixed to said vertical shaft, a plurality 110 of filters arranged in tiers in the vessel, and rectangular frames for carrying said filters, said frames being fixed at their outer ends to the inside of the settling vessel and connected together at their inner ends and arranged to provide passages between the filters from the top to the bottom of the vessel. 115

10. In apparatus for the purpose described in combination, a settling vessel, a conveyer for withdrawing the settled solids therefrom, a casing inclosing said conveyer, said casing communicating with the settling vessel, means for feeding the settled solids from the vessel to said casing, said means comprising a vertical shaft and radial blades or arms fixed to said vertical shaft, a plurality 120 of filters arranged in tiers in the vessel, and rectangular frames for carrying said filters, said frames being fixed at their outer ends to the inside of the settling vessel and connected together at their inner ends and arranged to provide passages between the filters from the top to the bottom of the vessel. 125

130

of filters arranged in tiers in the vessel, rectangular frames for carrying said filters, said frames being fixed at their outer ends to the inside of the settling vessel and connected together at their inner ends and arranged to provide passages between the filters from the top to the bottom of the vessel, and means for cutting the settled solids and scraping the same off the surfaces of the filters.

11. In apparatus for the purpose described in combination, a settling vessel, a conveyer for withdrawing the settled solids therefrom, a casing inclosing said conveyer, said casing communicating with the settling vessel, means for feeding the settled solids from the vessel to said casing, said means comprising a vertical shaft and radial blades or arms fixed to said vertical shaft, a plurality 20 of filters arranged in tiers in the vessel, rectangular frames for carrying said filters, said frames being fixed at their outer ends to the inside of the settling vessel and connected together at their inner ends and arranged to provide passages between the filters from the top to the bottom of the vessel, said latter means comprising radial arms fixed to the vertical shaft aforesaid, wires or

bands fixed to said arms and means for maintaining said wires or bands taut.

12. In apparatus for the purpose described in combination, a settling vessel, a conveyer for withdrawing the settled solids therefrom, a casing inclosing said conveyer, said casing communicating with the settling vessel, means for feeding the settled solids from the vessel to said casing, said means comprising a vertical shaft and radial blades or arms fixed to said vertical shaft, a plurality 30 of filters arranged in tiers in the vessel, and rectangular frames for carrying said filters, said frames being fixed at their outer ends to the inside of the settling vessel and connected together at their inner ends, the filters of each set or tier from the top to the 35 bottom of the vessel being made somewhat narrower and the carriers therefor made correspondingly wider for the purpose set forth.

In testimony whereof I have signed my 50 name to this specification in the presence of two subscribing witnesses.

ALEXANDER JOHN ARBUCKLE.
